PAPER CUTTER

David T. Helprin, New York, N. Y.

Application December 22, 1941, Serial No. 423,961

7 Claims. (Cl. 164—73)

This invention relates to cutting machinery, and more particularly to machinery designed to cut paper. In many operations involving the cutting and trimming of paper in the printing industry and in office work, it is desirable and essential that a plurality of sheets be cut accurately to a specific size. This is difficult with present equipment since most paper cutters are supplied with a knife having a shearing action which tends to cut unevenly when a substantial number of sheets are cut at one time.

The purpose of this invention is to provide a three-way cutter which will not only cut a large number of sheets accurately and cleanly but which may also be used as a rule, a measuring unit, and an accurate punch.

A further object is to provide a cutting machine in which the accuracy of the machine may be controlled to a very small fraction of an inch, and in which the cutting element must travel in the desired path.

A further object is to provide a device of the character described in which an inexpensive, replaceable cutting element, such as a razor blade, may be used.

With these and other objects in view, reference is had to the accompanying drawings, in which—

Fig. 1 is a plan view of a machine embodying my invention, partly cut away;

Fig. 2 is a cross-sectional view taken on the line 2—2 of Fig. 1;

Fig. 3 is a cross-sectional view taken on the line 3—3 of Fig. 1;

Fig. 4 is a cross-sectional view taken on the line 4—4 of Fig. 3;

Fig. 5 is a cross-sectional view taken on the line 5—5 of Fig. 1;

Fig. 6 is a view of a modified form of cutting element.

I provide a base 10 having a top 11. The top 11 is provided with a channel 12 running longitudinally of its length in a straight line. Mounted at one end of the top 11 are two pins 14 and 15 adapted to receive and position through openings therein a hinge member 16. Hingedly connected to the hinge member 16 is an arm 17. The arm 17 is rectangular in shape and is made up of two bars, one bar slightly wider than the other. The wider bar has an edge 18 which may be used as a rule; the narrow bar has a ruling edge 19. The inner edge of both bars is beveled to prevent the blade from cutting into the bars.

At the opposite end of the top 11 are two angle bars 20 and 21 firmly affixed to the top 11 by means of screws 22. The angle bars 20 and 21

are spaced to form an opening 23 so that the arm 17 may be positioned between them and firmly held to prevent any sliding movement. Mounted at either end of the arm 17 are the posts 25 and 26 and positioned through said posts is the rod 27. The rod 27 passes through the opening 28 in the post 26 and the corresponding opening 29 in the post 25 and is firmly positioned by means of a thumb screw 30.

10 Mounted for sliding movement on the rod 27 is a blade-carrying carriage 31. This carriage is provided with a plurality of rollers 32 which position the carriage on the rod 27 and prevent it from rocking. The bottom of the carriage 33 terminates above the arm 17 so that there is no contact between the arm 17 and the carriage. A handle 34 is provided for convenient operation of the carriage.

At the lower portion of the carriage there is 20 an angle plate 35 fastened to the carriage by a thumb screw 36 and positioned by the pins 37. The angle plate 35 is adapted to hold a razor blade 38 so that its cutting edge 39 will extend through the slot 40 in the arm 17. Since the 25 slot 40 is positioned immediately over the slot 12, the blade will extend through the arm into the slot 12.

It will be readily understood that paper, such 30 as indicated by the dotted lines 41, will be inserted under the arm 17 and the carriage 31 slid to the other end of the rod, thus cutting the paper along the slot 40 as desired. Since from time to time a large number of sheets will be placed in the cutter at one time, thumb screws 42 35 in the hinge members 16 and 43 at the end of the arm are provided to raise or lower the position of the arm. A latch 44 is provided to hold the arm in the down position, and it will be understood that by the use of the thumb screws 42 and 43 the arm 17 may be raised so that the 40 paper to be cut may be slid under the arm 17 without raising the arm for each operation. The carriage 31 is so mounted on the rod 27 that it will readily slide thereon. The pick-up of the 45 end of the arm 17 sufficiently to remove cut paper will be enough to cause the carriage 31 to return to the post 28. However, a reel 50 having a coil spring 51 with a thong 52 wound thereon 50 may be provided to automatically return the carriage as soon as it is released. The end of the thong 52 is engaged to the pin 53 and as the carriage is moved toward the operator the spring is wound. Immediately upon releasing the handle the spring and thong will return the carriage toward the post 28.

Scales 56 and 57 are provided so that the operator may readily measure the paper being cut. A movable stop 58 held on the angle bar 21 by means of the set screw 59 may also be used and a punch 60 may be mounted in an opening in the angle bar 21 to punch the paper after it has been cut. The punch 60 is held in position against the bracket 62 by a single screw 61 and is recessed into the top 11, as shown in Fig. 5. The bracket 62 is fastened to the angle bar 21. Since several sizes of holes may be desirable, the punch is readily replaceable by a larger or smaller one by the simple operation of removing the screw 61.

A holder for old blades is provided at 65, this holder consisting of two pins 66 and 67 to position the blades, a covering plate 68, and a screw 69 to hold the plate in position. It will be readily seen that when a blade is dulled or chipped, the angle plate 35 may be removed by taking off the screw 39 and the blade reversed on the pins 37. In order that the operator may know whether a blade has been used, a groove 70 in the end of the arm 17 is provided to break off the end of the blade as indicated at 72.

While for all practical purposes a carriage carrying a single blade is sufficient, certain types of work require cutting on both movements of the carriage. Where this type of work is required, a carriage 75 (as shown in Fig. 6) is useful. It will be appreciated that this carriage carries two blades 76 and 77 oppositely positioned so that the cutter may work regardless of which direction the carriage is moved.

It will also be appreciated that while I have shown the handle member 34 fastened by screws to the carriage, the entire assembly may be welded in one piece or made in any other convenient form.

I claim:

1. A paper cutting machine including a base, a channel in said base running longitudinally thereof, a hinge member at one end of said base astride said channel, an arm on said hinge member, a slot in said arm, posts adjacent each end of said arm, a rod mounted in said posts, a carriage slidably mounted on said rod, a cutting member on said carriage extending through said slot in said arm into said channel, and resilient means for yieldingly maintaining said carriage at one end of said rod.

2. A paper cutting machine comprising a base, an arm pivotally mounted at one end of said base, angle bars at the opposite end of said base adapt-

ed to engage the sides of said arm, a slot in said arm extending longitudinally thereof, a rod positioned above said arm, a carriage mounted for sliding movement on said rod said carriage being provided with spaced rollers engaging said rod, and a blade positioned on said carriage extending through said slot.

3. A paper cutting machine including a base, an arm hingedly connected at one end of said base, angle bars positioned adjacent the other end of said base, said angle bars being spaced to accommodate said arm, and a stop member mounted on one of said angle bars adapted to slide thereon and to be fixed at any desired position thereon.

4. A cutting machine comprising a base, a channel in said base, an arm pivoted at one end thereof astride said channel, angle bars on said base adjacent the opposite end thereof, said angle bars being spaced to accommodate said arm and to position said arm whereby each longitudinal edge of said arm and said angle bars will at all times form a right angle, a rod mounted on and above said arm, and a carriage carrying a cutting member slidably mounted on said rod.

5. A paper cutting machine comprising a base, a channel in said base, an arm pivoted at one end to said base, a carriage positioned above said arm for sliding movement, a cutting member in said carriage, and means for raising and lowering the position of said arm with relation to said base to vary the distance between said arm and said base when said machine is in operating position.

6. A device of the character described including a base, a channel in said base, an arm pivotally mounted at one end of said base, a pair of angle bars at the other end of said base mounted at right angles to said arm and at each side thereof, a scale parallel to said angle bars, an adjustable stop mounted on said angle bars, and a punch removably mounted on said angle bars.

7. A paper cutting machine comprising a base, a channel in said base, an arm mounted above said base, a slot in said arm, means for positioning said arm with relation to said channel, a rod mounted on and above said arm, a carriage slidably mounted on said rod, a cutting member carried by said carriage extending through said slot in said channel, a thong engaging said carriage, and spring means for exerting pressure on said thong to yieldingly maintain said carriage at one end of said rod.

DAVID T. HELPRIN.
